Primary Examiner — Mark Goodwin(74) *Attorney, Agent, or Firm* — Michael Best & Friedrich LLP**CLAIM**

The ornamental design for an escutcheon, as shown and described.

DESCRIPTION

FIG. 1 is a perspective view of an escutcheon showing my new design.

FIG. 2 is a front elevational view thereof.

FIG. 3 is a right side elevational view thereof.

FIG. 4 is a left side elevational view thereof.

FIG. 5 is a top plan view thereof.

FIG. 6 is a perspective view of an alternative escutcheon showing my new design.

FIG. 7 is a front elevational view thereof.

FIG. 8 is a right side elevational view thereof.

FIG. 9 is a left side elevational view thereof; and,

FIG. 10 is a top plan view thereof.

The rear view is not part of the claimed design. The broken line showing is for illustrative purposes only and forms no part of the claimed design.
